CLAIM

The ornamental design for a curio cabinet, as shown and described.

DESCRIPTION

FIG. 1 is a front perspective view of a curio cabinet showing our new design;

FIG. 2 is a side elevational view thereof; and,

FIG. 3 is a front elevational view of thereof.

The top, bottom and rear portions of the design are plain and unornamented. The dash line on the figures represent environmental hardware elements and are not a limitation of our invention.
